CLAIM

The ornamental design for LED makeup mirror, as shown and described.

DESCRIPTION

FIG. 1 is a top right perspective view showing LED makeup mirror, showing my new design;
FIG. 2 is a front elevation view thereof;
FIG. 3 is a rear elevation view thereof;
FIG. 4 is a side view thereof;
FIG. 5 is an opposite side view thereof;
FIG. 6 is a top plan view thereof; and,
FIG. 7 is bottom plan view thereof.

The broken lines in the figures are for the purpose of illustrating portions of the LED makeup mirror, which form no part of the claimed design.
